UNITED STATES PATENT OFFICE.

NORMAN J. MACLEAN, OF BAY CITY, MICHIGAN.

COOKING-UTENSIL CLEANER.

Application filed November 12, 1921. Serial No. 514,670.

To all whom it may concern:

Be it known that I, NORMAN J. MACLEAN, a citizen of the United States of America, residing at Bay City, in the county of Bay 5 and State of Michigan, have invented certain new and useful Improvements in a Cooking-Utensil Cleaner, of which the following is a specification.

The present invention is a scraper or 10 cleaner for culinary purposes and is particularly adapted for removing sticky or burnt substances from culinary utensils.

It is the object of the present invention to produce a device of the above stated 15 character which is extremely simple in construction, cheap to produce, durable and effectual in use. With these and other objects in view the invention resides in the sundry details of construction, combination 20 and arrangement of parts hereinafter more fully described and claimed.

In this specification and the annexed drawings, the invention is disclosed in the form in which it is considered to be the best; but the invention is not limited to such 25 form because it is capable of being embodied in other forms, and it is to be understood that in and by the claims following the description herein it is intended to cover 30 the invention in whatever form it may embody within the scope thereof.

In the drawings which clearly illustrate the invention,

Figure 1 shows a plane view of one embodiment of the invention wherein the cleaner is made in a circular form,

Figure 2 is the plane view of another embodiment of the invention wherein the cleaner is in an oval or elliptical form,

Figure 3 is a transverse sectional view of the cleaner taken substantially on line $a-a$ of Figure 2,

Figure 4 is a transverse sectional view taken on line $x-x$ of Figure 3 and illustrating the cross section of the wire composing the cleaner,

Figure 5 is a large fragmentary view of the coils composing the cleaner, showing two convolutions thereof and the position of the scraping edges of the wire composing the coil.

Figure 6 is a plan view of another embodiment of the invention,

Figure 7 is a fragmentary and enlarged 55 sectional view showing the position of the scraping edges of the cleaner in Figure 6.

Figure 8 is an enlarged fragmentary sectional view taken substantially on line B-B of Figure 6, and

Figure 9 is a sectional view taken substantially on line A-A of Figure 6.

The cleaner of this invention is made of a strand of wire, preferably a single strand, provided with a longitudinal scraping edge, the strand being wound in a spiral throughout its length, the spiral being bent or formed in any desired shape for convenient use and handling for the purpose of scraping or removing substances which have adhered to cooking utensils.

In the forms of the invention shown in the drawings, the cleaner C is composed, preferably, of a single strand of wire 1, substantially triangular in cross section as shown in Figures 4 and 5. However, this invention is not limited to triangular shaped wire as any form of wire will suffice having a longitudinal cutting edge 2. The wire is then wound to form a spiral 1 with the cutting edge 2 lying on the outer face of the spiral, see Figure 5. Of course, the convolutions of the spiral may be wound close together or spaced apart as may be desired in certain types of cleaners; however, in the present disclosure it is shown that the convolutions are slightly separated.

The spiral thus formed is then bent in any desired form or configuration which will be of a size and shape to fit in the hand, to be conveniently gripped thereby 90 and provide the ultimate cleaner. However,

as shown in Figure 1, the spiral 1 is coiled upon itself to produce a circular form of cleaner having an inner coil 3 and an outer coil 4. In Figure 2, the spiral is bent in an 95 elliptical or oval form having a central longitudinal portion 7 surrounded by the elliptical coil 5.

In both forms of the cleaner as shown in Figures 1 and 2, the scraping edge 2 is on the outer face of each convolution of the spiral and presents itself to the surface with which the convolutions come in contact. It can thus be seen that as the cleaner C is moved back and forth over a surface with a rubbing motion the scraping edges 2 of the spiral will remove the substances on the surface. The ends of the spiral are suitably attached or secured to other portions to maintain the form or shape 100

of the cleaner, as indicated at 10 and 11, in Figures 1 and 2, and 12 and 13, in Figure 6. Also other portions of the spiral may 105 110

be attached or secured together for the same purpose, as at 14, in Figure 6.

It is preferred to form the convolutions of the spiral so that they will assume a substantially square shape in cross section, as illustrated in Figure 3, with the corners of the square slightly rounded as at 6. The principal advantage of so forming the convolution is to increase its area of contact with its surface to be scraped, to produce in effect, by reason of the convolutions being arranged side by side and substantially overlapping, as shown in Figures 1, 2, 3, 6, and 8, a plurality of continuous scraping edges throughout the area of the cleaner, and to permit the corners 6 to reach into the corners of the utensils, which corners are usually formed with a rounding edge as illustrated by dotted lines in Figure 3. The form of scraper shown in Figure 6 is somewhat the same as that shown in Figure 1, except that the wire strand 1^a is so arranged and positioned that, by reason of the triangular formation of the wire in cross-section, two of the edges thereof will present beveled or knifelike scraping edges to lie at an inclination to the surface to be scraped, as clearly illustrated in Figures 7, 8 and 9. These inclined cutting edges are indicated at 15 and 16 and alternatively present themselves for a scraping operation as the cleaner is moved back and forth in a manner that will be clearly understood. It will be observed that the cleaner of this invention consists of a spirally wound strand of wire, the spiral being coiled or bent upon itself to form a number of lengths or portions arranged side by side and in the same plane throughout the area of the cleaner, thus producing a relatively flat and compact cleaner, with the flat edges of the convolutions of the spiral cooperating to provide cleaning edges across the entire area of the cleaner.

From the foregoing it will be seen that by the present invention a very simple and economical culinary cleaner is produced, there being only a single strand of wire involved in this structure but which is of such shape and form that renders it most efficient for its purpose.

Having thus described my invention in the embodiment in which it is at present devised, what I claim as new and novel and desire to obtain Letters Patent for is:

1. A culinary cleaner comprising a body member formed from a strand of wire wound to form a spiral having regular and substantially rectangular convolutions, corresponding sides of the said convolutions lying in the same plane.

2. A culinary cleaner comprising at least one strand of wire wound to form a spiral, having substantially rectangular convolutions having corresponding sides lying in the same plane, the said spiral being bent upon itself to form a substantially flat and compact body, the said bent or looped portions of the spiral being secured together to maintain the shape of the body, the outer faces of the said convolutions of the spiral each having a scraping edge thereon and the outer corners of the convolutions being rounded.

3. A culinary cleaner composed of a wire strand having a flat surface extending longitudinally of the strand, said strand being wound to form a spiral, and said spiral being coiled upon itself to form a substantially flat and compact body member, to be gripped by the hand, said flat surface of the wire lying on the outer surface of said body to provide scraping edges and to present itself to surfaces with which the cleaner contacts.

In testimony whereof I have affixed my signature.

NORMAN J. MACLEAN.
